JACK ELEMENT

Earl G. Gunn, Jackson, Mich., assignor to Walker
Manufacturing Company, Racine, Wis., a cor-
poration of Wisconsin

Application September 9, 1938, Serial No. 229,059

2 Claims. (Cl. 254—106)

This invention relates to an improved lifting plate for friction type jacks. The invention also relates to the novel method of forming the improved lifting plate and a unique type of tool intended for practicing the novel method.

Lifting plates of the type herein disclosed are primarily intended for use in friction type lifting mechanisms such, for example, as vehicle jacks of the type illustrated in applicant's prior co-pending application Serial No. 191,050, filed February 17, 1938.

In jack mechanisms of this general character, the lifting plates are designed to have an aperture therein very slightly larger than the outside diameter of the lifting standard with which the plates are associated whereby, upon the tilting of the lifting plates, they will frictionally engage the surface of the standard and positively grip the same.

In applicant's prior co-pending application, a jack mechanism is illustrated which employs a plurality of superimposed lifting plates each adapted to operate more or less independently of the other and adapted to frictionally engage the exterior surface of the standard independently of each other whereby to distribute the load throughout a relatively large number of individually separate areas.

The utilization of a plurality of lifting plates of this general type serves not only the purpose of distributing the load but permits the manufacture of the plates from a relatively thin sheet metal stock whereby the same may be stamped in an ordinary punch press from sheet metal instead of having to be forged or otherwise formed.

Considerable difficulty has been experienced in the fabrication of sheet metal lifting plates of this generic type in that in a stamping operation, extremely close engineering tolerances can not be maintained and, therefore, the sharp corners of the aperture have a tendency to score and deform the exterior surface of the lifting column.

It is a primary object of the present invention to provide a relatively simple, cheaply manufactured lifting plate structure which is preformed in such a way that it has a small but well defined area which is adapted to engage the exterior surface of the column and, therefore, operates with maximum efficiency immediately upon installation of the jack mechanism.

Still further, the invention contemplates the provision of a novel method of fabricating such lifting plates in such a manner that the metal around the aperture of the plate which is adapted

to engage the lifting column is preformed precisely to the desired configuration prior to the assembly of the mechanism.

Still further, the present invention contemplates the provision of a novel form of tool constructed and arranged to practice the novel method set forth in the preceding paragraph.

Still other and further objects, advantages, and features of the present invention will become clearly apparent from the following specification when considered in connection with the accompanying drawing forming a part thereof.

In the drawing:

Figure 1 is a top plan view of a lifting plate embodying the novel features of the present invention and formed by means of the method of the present invention.

Figure 2 is a fragmentary side elevational view with parts in section illustrating the manner in which the improved lifting plate is adapted to frictionally engage a supporting column of a lifting mechanism.

Figure 3 is an enlarged fragmentary sectional view disclosing the novel configuration of the aperture in the lifting plate when formed by the method of the present invention.

Figure 4 is a fragmentary transverse sectional view of the lifting plate shown in Figure 3, disclosing the same in an intermediate stage of manufacture.

Figure 5 is a top plan view of the tool utilized for forming the improved lifting plate structure.

Figure 6 is a side elevational view of the tool shown in Figure 5.

Figure 7 is a bottom plan view of the tool shown in Figures 5 and 6.

With more particular reference to the drawing, the lifting plate 10 illustrated in Figure 1 is of the type designed and intended for use with friction type jacks and is of generally circular configuration except for the fact that it has a projecting lug or ear 11 which is adapted to be engaged by the plate canting mechanism in order to cant the plate with respect to the lifting column with which the plate is subsequently to be associated. 45 This lifting plate is preferably formed from cold rolled steel or similar material of a thickness sufficiently thin so that it may be stamped to the configuration shown and as an initial stage in the operation, the lifting plate has an aperture 50 12 formed therein. This aperture 12 may be punched out during the stamping operation as is conventional in the formation of articles of this kind.

After the lifting plate has thus been stamped 55

out roughly to the finally desired form, the axial ends of the aperture 12 are counter-sunk as at 13 at approximately a 45° angle. The advantage and purpose of this counter-sinking operation 5 will be readily apparent hereinafter. The lifting plate then assumes the form illustrated in Figure 4 of the drawing, and is ready for treatment by means of the tool shown in Figures 5, 6, and 7. This tool 15 is formed of suitable hard metal 10 stock and is constructed and arranged to provide a pair of substantially cylindrical surfaces 17 which are arranged converging toward each other and are formed on radii substantially identical to the radius of the lifting column with which the lifting plate is subsequently to be associated and 15 which radius is, therefore, substantially identical with the radius of the aperture 12 formed in the lifting plate 10. This tool is forced into the aperture 12 and obviously will engage the interior 20 surface of the aperture in the lifting plate at the point of intersection of the counter-sink and the cylindrical portion of the aperture. As this tool is forced into the lifting plate 12 in the manner illustrated in Figure 4, it will serve to crush the 25 metal of the lifting plate to form relatively small but well defined areas 18 on each of the opposite sides of the aperture 12. In view of the fact that the tool 15 is provided with the cylindrical surface portions 17, it will be apparent that these cylindrical surface portions 17 will form the surfaces 30 18 of the lifting plate so that they will lie in a cylindrical surface defined by introducing the lifting column 20 into the aperture 12 and inclining its axis at the angle of convergence of the 35 tool 15.

In accordance with the present method, the tool 15 may first be inserted from one side of the lifting plate to form the surfaces 18 and subsequently inserted from the opposite side to form 40 similar surfaces 22, or a pair of tools similar to the tool 15 may be simultaneously inserted into the aperture of the lifting plate from opposite sides. In any event, the lifting plate in its final 45 form will have the conical surfaces 18 and 22 formed therein adjacent opposite axial ends of the aperture 12.

It will be readily appreciated that the counter-sinking operation performed prior to the last described operation serves to provide an obtuse angled surface which gives support for the metal at 50 the point of intersection of the counter-sink and the surface portions 18 and 22 of the aperture and thus prevents forming a burr on either the upper or lower surfaces of the plate and permits accurate forming of the interior of the aperture.

It will be readily appreciated that when a lifting plate has been completely formed and is provided with an aperture having an interior configuration as the aperture shown in Figure 4 of the 60 drawing, this lifting plate may be mounted on a lifting column as is shown in Figure 2 of the drawing and that when the lifting plate is tilted at a slight angle to the perpendicular with respect to the axis of the lifting column 20, one of the sur-

faces 18 on one side of the aperture and one of the surfaces 22 on the opposite side of the aperture will smoothly and frictionally engage the surface of the lifting column thereby locking the plate in predetermined position with respect to 5 the column. In this way, the load carried by the lifting plate is distributed throughout a small but precisely defined area which area has a configuration such that substantially all points within the area will lie in a cylindrical surface common 10 to both the column and the interior surface of the lifting plate thereby materially reducing the unit pressure which would be encountered in the event the sharp corners of the counter-sink were permitted to directly engage the surface of the lifting 15 column.

It will still further be appreciated that the formation of the areas 18 and the areas 22 makes the lifting plates perfectly symmetrical so that it is entirely immaterial whether they are assembled 20 right-side-up or up-side-down with respect to the lifting column with which they are to be associated. The construction described also obviously serves to preclude the possibility of the sharp corners of the aperture deforming the surface of the 25 lifting column and from the very first permits smooth, satisfactory operation of the lifting plate mechanism with respect to the column.

It will be readily appreciated from the foregoing that the above described construction is one 30 which is exceedingly simple and cheap to manufacture. The method performed is simply, easily, and cheaply practiced, and the tool used for performing the method is unique and at the same time cheap and simple.

It will be readily apparent to those skilled in the art that many other and further modifications of the structure above described may be made yet at the same time falling within the scope of the invention as defined in the subjoined claims.

What is claimed is:

1. A lifting plate for friction type elevating mechanisms, comprising a metallic member having an aperture therethrough, the axial central portion of said aperture having walls lying in the 45 surface of a cylinder whose axis is normal to the plane of said plate, and zones adjacent said cylindrical surface lying in the surfaces of cylinders whose axes are inclined to the axis of said first mentioned cylinder.

2. A lifting plate for friction type elevating mechanisms, comprising a plate-like member having an aperture therethrough, the axial central zone of said aperture having walls lying in the surface of a cylinder whose axis is normal to the 55 plane of said plate-like member, the axial ends of said aperture being countersunk, the walls of said aperture on each side of said plate having a pair of zones lying between said counter-sink and said cylindrical zone which lie in the surface of 60 cylinders whose axes are inclined to the axis of said first mentioned cylinder.
